ARRANGEMENT FOR THE AUTOMATIC ADJUSTMENT OF FORMS AND THE TABULATING IN BOTH THE VERTICAL AND HORIZONTAL DIRECTION FOR TELEPRINTERS AND THE LIKE

Johann Augustin, Pforzheim, Germany, assignor to International Standard Electric Corporation, New York, N.Y., a corporation of Delaware

Filed Mar. 18, 1958, Ser. No. 722,298

Claims priority, application Germany Mar. 22, 1957

12 Claims. (Cl. 178—4.1)

In teleprinting operation it is often desired to effect a printing of the message on a certain form, such as on a bill of accounts, a form containing static statements, etc. To this end forms are used which are arranged continuously on an endless sheet of paper and which are provided with feed holes near the left and right edges of the paper for feeding purposes. It is absolutely necessary that the position of the paper form will be exactly the same with respect to the printing point at both the transmitting and the receiving stations. Otherwise the message at the receiving station would not be printed in the correct place on the form so as to correspond with that at the transmitting station.

In order to obtain a synchronous movement of this length of paper at both the transmitting and receiving stations the operators at the transmitting as well as at the receiving station will have to bring the forms into a corresponding position prior to the transmission of a message at both the transmitting and receiving stations. This however, requires that the receiving station be an attended station, i.e., that an operator be present for manually bringing the form into the proper position (adjusting to an identification mark) at the beginning of the message transmission. In order to obtain form synchronism without an operator having to be present at the receiving station, it is proposed, in accordance with the invention, to switch on the form synchronizing device by a signal or signal combination, such as "Figs." and "Who are you" (tripping of the call-back device) and to feed the paper in a step-by-step manner in the vertical direction by successively depressing the keys "Linefeed" and "Rpt." According to a further feature of the invention the paper feed is arranged to be interrupted by the action of the well known paper control contact, and a counting mechanism is arranged to count the number of paper feeding steps, until finally, upon reaching the required maximum number of steps the repeat key will be put out of operation either electrically or mechanically.

Instead of the repeat key (Rpt.), a special key may be provided for this purpose. The counting mechanism is adjustable so that the number of the line feed steps to be counted may be varied in accordance with the size of forms. The counting mechanism may also be modified so that it will not comprise one, but in connection with the method used with respect to horizontal tabulators, several riders, so that it will also be possible to carry out a vertical tabulation in accordance with the different paragraphs occurring within the text on the form.

The inventive arrangement bears the advantage over other conventional types of arrangements that it may be used without further ado with teleprinters connected to the public teleprinting network, because no special functions are transmitted or carried out which would be likely to disturb the public subscriber dialling operation, or would interfere in the case where a teleprinter provided with the inventive arrangement is connected with a standard type of teleprinter.

The construction as well as the mode of operation of the inventive arrangement for obtaining the form synchronism will now be described in the following with ref-

2

erence to an example of embodiment shown in FIGS. 1 through 8 of the accompanying drawings, in which:

FIG. 1a shows the printing paper at the transmitting station.

5 FIG. 1b shows the printing paper at the receiving station.

FIGS. 2-7 show various views and sections of the mechanical arrangement of the invention.

FIG. 8 shows a wiring diagram of the invention.

10 First of all there is shown in FIG. 1 a conventional type of paper length 7' on which successive forms 5' are printed. These forms may be separated along a perforated line 6' upon being filled in by the teleprinter. On both sides of the paper length feed holes 1' are provided and each form printed on this length of paper is provided with an identification mark 4' and with a paper contact hole 2'. At the transmitting teleprinter station the identification mark on the form to be filled in is brought into agreement with the marking provided on the teleprinter (FIG. 1a). At the opposite station the form may be in any other position in the teleprinter (FIG. 1b).

Thereupon the teleprinter at the opposite station will be called and both teleprinters will start to operate. Thereupon, at the calling teleprinter station, the FIGS.

25 key will be depressed, which will have to be depressed prior to operating the "Who are you" key. Upon actuation of the "Who are you" key, the engagement push-bar, denoted by 1, will be actuated by the pull-bar "Who are you," and will take along the lever 2 out of the position indicated by the dot-and-dash line into the position indicated by solid lines (FIG. 2). Apart from this operation the call-back device will be released in the conventional manner at the called teleprinter station.

30 The stepping ratchet pawl 5 pivotally attached to the lever arm 6, which has been lifted by the roller 3 on the lever 2 out of the ratchet wheel 27 via the pin 4, and which is capable of acting upon the push-bar 7 for the linefeed, as well as the ratchet 8, lifted out of the ratchet wheel 27 by the action of the operating edge 10 on the lever 2 via the lever 9, will engage the ratchet wheel 27 of the line counting mechanism.

35 This line counting mechanism consists of a ratchet wheel 27, a stepping ratchet pawl 5 on the lever 6, and the coupling lever 2, as well as the sensing lever 21 (FIG. 45) which cooperates with the camplate 24, and the spiral spring 25. During the coupling process of this line counting mechanism (engagement of the pawls 5 and 6), the line contacts *a* and *b* are momentarily closed by a short

50 lifting of the latching pawl 13, under the action of the tooth 18 provided on the lever 2 and via the contacting actuator 19 (FIGS. 2 and 8). The electromagnet 1a (FIGS. 5 and 8) will be energized for a short time and will move the push member 32 and the lever 33 towards the left via the magnet lever arrangement (armature 48, lever 29, shaft 30, lever 31). This will release the latching pawl 37 which, via the depressed "Who are you"

55 key with the lever 42 and 41 will move the levers 39 towards the right and will thus release the call-back device via the lever 37 and the releasing lever 47. At the same time the coupling pressure lever 40 will engage the one-speed clutch 43 and the transmitter driving shaft 45 will drive the transmitting cam cylinder 44.

60 On the form of the teleprinter at the opposite station and on the form of the teleprinter at the calling teleprinter station the name of the called teleprinting subscriber will now be printed. The called teleprinting station will now automatically carry out the carriage return and the line feed and will transmit the signal "Here is." The name of the called subscriber will now be typed by the calling and the called teleprinter.

65 70 Up to now there is no synchronism between the forms

on both the transmitting and receiving ends, and the written text is not yet typed at the place provided for it on the filled-in first form at the receiving end (FIG. 1b). In order now to bring the form in the teleprinter of the called subscriber, into the same position as at the calling subscriber the line feed key will be depressed and thereupon the repeat key 35 (FIG. 5) will be actuated. In the teleprinter of the calling subscriber the short-stroke or micro switch 49 (FIG. 4) is now closed, because the feeler 56 was permitted to engage the contact hole 2' on the paper length 7' after being adjusted to the identification mark 4' (FIG. 1a). In FIG. 4 the contacts *g* and *h* of this particular teleprinted are now closed. The transmitter driving shaft 45 will continuously drive the transmitting cam cylinder 44 via the engaged one-speed clutch 43, and, via the teleprinter line circuit the line feed signal will be continuously transmitted to the teleprinter set of the called subscriber. At each line feed operation, the counting mechanism in the teleprinter of the calling subscriber, which is engaged via the lever 2 (FIG. 2), will be stepped on by one tooth. However, a line feed will not take place, because the line feed previously carried out for the functional operation "Who are you" and "Here is" has turned the cam-plate 24 so far that the sensing lever 21 is now positioned on the inclined right-hand portion of the notch 23. The contacts *c* and *d* are now closed and the relay 2a (FIGS. 4 and 8) is energized. Upon attraction of the armature of the electro magnet, the coupling lever 53 between the lever 54 and the lever 6 will be released, so that the counting mechanism will be further transported by the line feed lever 7 and the pawl 5, but no line feed takes place via the rodging 51, 52, the pull ratchet lever 50, and the switching wheel 58 of the platen 59. However, in the called teleprinter set a line feed will be effected until the sensing lever 56 is permitted to engage the contact hole 2' on the paper length 7'. When this occurs the electromagnet 2a will operate the coupling pawl 53 will be unlatched, and the line feed interrupted. The counting mechanism in the transmitting teleprinter, as well as in the receiving teleprinter at the opposite station will now rotate until the releasing pin 46 on the ratchet wheel 27 meets the lever 14 the ratchet pawl 13 which, thereupon, will release the latching lever 2 under action of the spring 16. This lever 2 will now jump back into its normal position and will thereby disengage the pawls 5 and 8 from the teeth of the ratchet wheel 27. On account of this, the ratchet wheel 27 with its camplate 24 will likewise leap back to its initial position by the action of the spiral spring 25, which has been tensioned by the counting of the line feed operations.

Upon lifting of the ratchet pawl 13 by the releasing pin 46 the contacts *a* and *b* will be closed. The electromagnet 1a will be energized and will put the repeat key 35 out of operation via the magnet rodging 29, 30, 31, the push member 32 and the coupling lever 33, and the one-speed-clutch 43, by the engagement of the clutch pressure lever 40, will separate the transmitter driving shaft 45 from the transmitting cam cylinder 44. To the operator of the calling teleprinter this is a sign that the form in the teleprinter at the opposite station is in the same position as the form in his teleprinter. This condition will be noticed acoustically by the standstill of the disengaged or decoupled transmitter driving shaft 45. In a simple way this condition may also be indicated acoustically (buzzer) or optically (lighting of a lamp).

The electromagnet 1a may be used at the same time for the tabulator in the direction of the lines (FIGS. 6 and 7). The tabulator for a teleprinter in the line direction is described in the U.S. Patent 2,956,120 issued Oct. 11, 1960, to G. Grinsen and J. Augustin. This tabulator consists of several tabulating riders 60, adjustable on the tabulating bar 62, which is arranged in a swinging fashion between the levers 63. As soon as one tabulating rider 60 meets against the limit stop 61 of the holding device

66 at the type bar carriage, the tabulating bar 63 will be pressed upwardly and the bar 64 additionally provided at the levers 63 will, move downwardly and close the contacts *e* and *f* within the housing 65. These contacts are 5 arranged in parallel with the contacts *a* and *b* (see FIG. 8) and will cause the attraction of the electromagnet 1a when too close to disengage the coupling lever 33 and disable the repeat key 35 in the same manner as already 10 described. The type bar carriage will then come to a standstill because the continuous transmission of the signal "space" will be interrupted.

Now again a text may be transmitted and, thereupon, by actuating the repeat key, the signal "space" will be transmitted until the next successive rider 60 again 15 disables the repeat key. Accordingly, the same electromagnet 1a may be used to carry out not only the adjustment as to a uniform position of the forms but also tabulation in the direction of the lines.

Now the counting mechanism is devised in such a 20 way that it will count the line changes from the contact hole 2 to the next contact hole 2, in the most extreme case e.g. in the case of a paper sheet having the size of DIN A4 (size A4 according to German Industrial Standards=210×297 mm.) so that a corresponding line feed 25 will be obtained. When filling-in forms having a smaller size, such as DIN A5 (148×210 mm.), then there would be too long a time before the releasing pin 46 permits the counting mechanism to jump back into the initial position. This however, may be taken care of by inserting a second 30 releasing pin 46 on the ratchet wheel 27, permitting the line counting mechanism to return to the initial position correspondingly earlier.

Furthermore it is conceivable that a vertical tabulation 35 in relation to the direction of the lines can be carried out with the aid of the counting mechanism as well a tabulation in the direction of the lines. This may be accomplished in such a way that the releasing pin 46 and the ratchet wheel or counting wheel 27 of the counting mechanism will act upon adjustable riders, which are capable 40 of being displaced along a path concentric in respect to the counting wheel within a notch. A contact is fixed to each rider which, upon lifting of the rider, is closed by the releasing pin 46 and is arranged in parallel with the contact *e*, *f* (FIG. 7). Just as is the case of the tabulation 45 in the direction of the lines, so in this case the repeat key will be interrupted. Provisions are made to prevent the actuation of the contacts attached to the counting mechanism upon the return thereof to its initial position by a 50 corresponding design of the riders or of the releasing pin.

While I have described above the principles of my invention in connection with specific apparatus, it is to be clearly understood that this description is made only by 55 way of example and not as a limitation to the scope of my invention as set forth in the objects thereof and in the accompanying claims.

What is claimed is:

1. Apparatus for automatically bringing into positional 60 registration and for tabulating purposes, forms to be printed upon by respective transmitting and receiving printing telegraph machines of the kind having automatic line feed mechanisms and letter space feed mechanisms, electrical contact sensing means in cooperative engagement with the transmitting and receiving forms for rendering the line feed mechanism at the transmitting machine ineffective on the transmitting form until the transmitting and receiving forms are in the proper positional registration, and means for causing the line feed mechanism at the receiving machine to operate in response to line feed signals from the transmitting machine until the receiving form is in the proper positional registration with the transmitting form.

2. Apparatus according to claim 1 in which means are 70 provided and operative while the normal line feed mechanism of the transmitting machine is ineffective, to trans-

mit a series of line feed signals to the receiving machine without effecting corresponding line feed operations at the transmitting machine.

3. Apparatus according to claim 2 in which the means for controlling the transmission of said line feed signals to the receiving machine includes a repeat key at the transmitting machine.

4. Apparatus according to claim 1 in which the means for rendering the normal line feed mechanism at the transmitting machine ineffective on the transmitting form includes a key for transmitting a special telegraph signal.

5. Apparatus according to claim 4 in which each machine has a normal "call back" mechanism including a "call back" tripping device, said mechanism being interconnected with the line feed mechanism and rendered operative by the same signal transmission which operates the said "call back" tripping device for causing the transmitting machine to transmit line feed signals to the receiving machine without corresponding line feed operations on the transmitting form.

6. Apparatus according to claim 1 in which a counting device is provided for counting the number of said successive line feed operations effected at the receiving machine, and means controlled by the said contact sensing mechanism at the receiving machine for transmitting an indication control signal back to the transmitting machine when the requisite number of line feed operations has been performed at the receiving machine to bring the receiving form into said proper registration.

7. Apparatus according to claim 6 in which means are provided at the transmitting machine and responsive to said indication control signal for temporarily disabling the repeat mechanism at the transmitting machine.

8. Apparatus according to claim 7 in which the said control signal transmitted back to the transmitting machine from the receiving machine produces an acoustic indication.

9. Apparatus according to claim 7 in which the said control signal transmitted back to the transmitting machine from the receiving machine produces an optical indication.

10. Apparatus according to claim 7 in which the repeat key at the transmitting machine which controls the transmission of said line feed signals is provided with means for locking it in operated condition until the receipt of said indication control signal.

11. Apparatus according to claim 1 in which a counting device is provided for counting the number of said successive line feed operations at the receiving machine, and said counting means has an adjustable element for controlling the number of line feed signals to be transmitted to the receiving machine in accordance with the size of the transmitting and receiving forms.

12. Apparatus according to claim 1 in which the transmission of said line feed signals is controlled by a repeat key at the transmitting machine and an associated electromagnet which electromagnet forms part of the normal letter space tabulating mechanism of the transmitting machine.
